DAVYDD C. HUGHES, OF CHICAGO, ILLINOIS, ASSIGNOR, BY MESNE ASSIGNMENTS, TO ADDRESSOGRAPH COMPANY, OF CHICAGO, ILLINOIS, A CORPORATION OF ILLINOIS.

TYPE-PLATE FOR PRINTING-MACHINES.

1,195,226.

Specification of Letters Patent. Patented Aug. 22, 1916.

Application filed September 6, 1910. Serial No. 580,546.

To all whom it may concern:

Be it known that I, DAVYDD C. HUGHES, a citizen of the United States, and a resident of Chicago, Cook county, Illinois, have invented certain new and useful Improvements in Type-Plates for Printing-Machines, of which the following is a full, true, clear, and exact description, such as will enable others skilled in the art to which it appertains to make and use the same.

My invention relates to type plates or type holders, and particularly to the kind which are used in connection with printing and addressing machines and the like.

The object of my invention is to provide a type plate or type holder of the class above described having channels or grooves adapted to receive and contain individual type set up in line to form or represent a name, address or other printing matter and to secure the type in position by forming integral means coöperating or co-acting with the walls of said channels and with the type to prevent movement of the type in the channels.

A particular object of my invention contemplates the provision of a type plate or type holder having a channel or groove for receiving and containing type, and further contemplates the forming of integral type stops or raised portions within the channel for maintaining the type against longitudinal movement therein, said raised portions being formed after the type have been placed in the channel and arranged preferably to hold the type under compression.

A further object of my invention contemplates the releasing or liberating of the type by de-forming or effacing the raised portions on type stops, thereby permitting the type to be removed from their channels wherever desired.

My invention will be more readily understood by reference to the accompanying drawings in which:

Figure 1 is a view of a type holder containing removable type, this view showing the integral type stops at each end of the lines of type in the channels of said holder for maintaining the type against longitudinal movement; Fig. 2 is a similar view of a type holder showing several lines of type ready to be locked or secured in their channels by the formation of integral holding

means; Fig. 3 is a side elevation, partly in section, showing the tool or device adapted for forming or effacing the holding means in the type holders; Figs. 4, 5, 6 and 7 shown are enlarged sectional views taken longitudinally of one of the channels and showing a method of forming and effacing the type stops or holding means; and Fig. 8 is an enlarged transverse sectional view on line 8—8 of Fig. 1.

It is readily manifest that my invention is applicable to various forms of type holders or type plates, such as used in connection with printing and addressing machines; hence I will describe one form thereof which is particularly adapted to the portable unit type holders used in the "Rogers" system.

A type holder of this class is depicted in the drawings wherein—1 indicates a substantially rectangular metallic plate having a plurality of channels or grooves 2 on its upper face in parallel relation, in which grooves are contained lines of individual type 3 arranged in proper relation to print, when the holder is in operation, the subject matter for which the type are set up.

The drawings clearly show that the "Rogers" type holder has all of the parts necessary to make a complete holder formed up integrally from a single sheet of metal. These type holders are usually stacked up or filed in a filing cabinet and are arranged in the cabinet drawers in a substantially vertical position, one behind the other, in the manner of an ordinary card index. When it is desired to print the subject matter which the type in these type holders represent, the drawer is removed from the cabinet and the type holders are placed usually in a vertical stack in the magazine of a printing or addressing machine, and from this stack they are removed one by one and carried through the machine to perform their printing operation after which they are deposited again in the drawer in their original relation. Each type holder has two depending flanges 6 on its under face adjacent each side edge thereof for the purpose of spacing and protecting the type holders in the cabinet drawer and in the magazine of the machine, and for the purpose of guiding the holders in their course through the machine. Each plate also has on its side edges a pair of laterally projecting ears or

lugs 7 having depending hooks 8 for engaging the side edges of the drawer to maintain the type holders in proper position therein. Each holder is also provided with a blank portion on its upper face at the side of the type channels upon which information cards 9 are placed, these cards being for indexing and filing purposes and for other information of value in a system of this sort. By reference to Fig. 8 it will be seen that the channels 2 are formed by crimping or folding up a number of parallel ribs 4 from the metallic plate 1. The upper edges of the ribs are expanded laterally or flattened out to form overhanging flanges 5 which narrow or reduce the width of the entrance of the type channels. The individual type which are used in these holders are preferably metallic and have grooves in their side faces which register with and engage the overhanging flanges 5 of the holder. This arrangement holds the type against movement in the channels in all directions except longitudinal of the channel. The types are inserted into the ends of the channels to form lines of type which are shifted longitudinally of the channels to the desired position. It is now seen that some means should be provided which will securely hold or retain the type against longitudinal movement in the channels after said type have been placed in their proper position, and that this means should be conveniently removable in order that the position of the line of type may be changed or may be entirely removed if desired; that this means should be inexpensive, simple and convenient to handle and adaptable to various lengths of lines of type and various positions thereof in the channels. I meet all of these requirements by providing holding means or type stops in the form of beads or raised portions 10 preferably struck up or integrally formed from that portion of the type holder which supports or constitutes the bottom wall of the type channels. These raised portions constitute stops within the channels against which the type abut and which accordingly prevent longitudinal movement of the type in the channel. It is obvious that while stops hold the type against longitudinal movement they also co-operate or co-act with the ribs and flanges to limit or restrict the movement of the type in any direction. They may be of any suitable shape and may be struck up from the plate by any suitable means or in any desired manner. I prefer, however, to make them in the form of inclined beads or raised portions struck up from the plate 1 by distorting a portion of the plate within the channels adjacent the end type therein (as shown in Figs. 4 to 7 inclusive). These beads are cut away from the main portion 65 of the plate at point 11 against which the

type abut so as to form a sort of right-angled shoulder for the reception of the lower corner of the type. I prefer to form these beads or raised portions by means of a hand tool, the advantage being that it is simple and convenient and offers a satisfactory means by which the operation may be performed in an ordinary business office, and without the necessity of an expensive power-operated punch press. The preferred form of this tool is shown in Fig. 3. It comprises a body portion or member 15 having an elongated slot 16 for the reception of the type holders and at the same time it provides a pair of relatively stationary jaws embracing the type holders. The upper jaw is provided with a fixed female die 17 projecting into the slot 16 at right angles thereto and suitably formed on its end 18 for co-operation with the end 19 of a male die 20 carried in the under jaw. The male die 20 is arranged to reciprocate in a suitable bearing to and from the fixed die 17 and is moved by means of a compression member or lever 21 pivoted at 22 to the member 15. This lever has an arm 23 which is engaged by the short arm 24 of an operating handle 25 pivoted at 26 to the jaw member 15. A spiral spring 27 serves to normally maintain the male die in a retracted position. This arrangement forms a powerful lever system by which a clean cut bead may be formed in the metal without any great amount of effort on the part of the operator. The jaw member 15 also has another slot 28 and another operating lever 29 which operates a die 30 through a system of levers identical with that which operates the die 20. The purpose of this set of dies will be hereinafter described.

By reference to Figs. 4, 5, and 6, I will now describe the method of securing the type in proper position in the channels of the plate or holder. I place a line of type 3 in the desired position in the channel of a type holder and bring the tool into position so that the die 17 abuts against one end of the line of type. The dies are then brought together to upset or strike up that portion of the plate 1 adjacent the end type in the channel. This bead having been formed, the tool is brought into position with respect to the other end of the line of type, as shown in Fig. 6, and a similar bead or raised portion formed in the plate 1. It will be noted that the die 17 projects down into the type channel to a point very close to the bottom thereof. The side or vertical edge 17' of the die is disposed substantially parallel to the side face of the end type. By arranging the die in this manner the tool may be moved longitudinally of the slot member to compress or jam the line of type tightly against the first abutment or stop which has been formed, and the type held

in this compressed condition while the tool is operated to form the second bead, as shown in Fig. 6. In this manner the type are securely held between the two abutments 5 or stops and their movement along the slot accordingly restricted. One advantage of my invention lies in the fact that the type may be positioned at any point along the channel and the type stops may then be 10 formed to hold the type in this position, thus making the invention adaptable to any length of type or to any position thereof in the channel. It often happens, however, 15 that the subject matter which the type represent must be changed thus making it desirable that the stops be capable of removal from the channels. The preferable way of 20 removing the stops is to simply deform, efface or flatten them. I de-form or efface the beads by means of another set of dies 25 30 and 31 so formed that they flatten the beads and render them flush with the bottom wall of the channel, thus leaving the type channel free and clear of any obstruction 30 and thereby making it possible to easily remove the type. The dies 30 and 31 are 35 preferably operated in identically the same manner as the other set. They are, however, flat-ended or flat-faced so that when pressed together they compress the bead into its original condition, that is, flush with the plate 1, as shown clearly in Fig. 7. After the desired changes have been made 40 in the arrangement of the type, other beads

may be struck up at the proper places in the 35 type channel.

Obviously the beads may be of any suitable form to suit the requirements of the particular style of type holder with which they are associated. Any desirable form of 40 tool may be used for performing the operation of upsetting or distorting the metal to form these beads and for effacing them, whichever is found best adapted to this work. 45

Thus it is seen that my invention is capable of various modifications without departing from the spirit thereof and is to be so construed. 50

I claim:

A sheet metal type holder constructed to provide a channel adapted to receive a plurality of alined individual type, and means to secure said type against movement longitudinally of said channel comprising integral beads struck up from the bottom of said type channel intermediate of the outside ends thereof and having flat edges abutting the sides of the type at the ends of the line of individual type. 55

In testimony whereof, I have hereunto set my hand this 22nd day of August, 1910, in the presence of two subscribing witnesses. 60

DAVYDD C. HUGHES.
